UNITED STATES PATENT OFFICE.

MEIER G. HILPERT, OF BETHLEHEM, PENNSYLVANIA.

CHILD'S SLIDE.

Application filed October 31, 1925. Serial No. 65,991.

This invention relates to exercising and amusement slides for children, and relates more particularly to slides of this type which are adapted to be easily portable by a child 5 and to utilize as supports such articles as stairways, chairs, beds, tables and the like.

The present invention is a modification of or improvement over the child's slide disclosed in my co-pending application Serial 10 No. 649,966, filed July 6, 1923.

It is an object of this invention to cheapen and simplify the construction of a slide of the general type disclosed in said prior application, without sacrificing its strength or 15 durability.

It is a further object of this invention to provide a slide with a delivery platform pivoted thereto which may be folded back against the body of the slide in such a manner 20 as to permit easy packing, storing or shipping thereof.

It is a further object of this invention to provide a slide with wheels whereby it can be trundled from place to place by a child.

25 Other objects and advantages of my invention will be apparent from the following description, taken in conjunction with the accompanying drawings, which form a part of this specification, and in which:

30 Figure 1 is a plan view of a slide constructed in accordance with the present invention;

Figure 2 is a side elevation thereof;

Figure 3 is an enlarged cross section taken on the line 3—3 of Figure 1;

35 Figure 4 is an enlarged fragmentary longitudinal section taken on the line 4—4 of Figure 1;

Figure 5 is a detail view of a portion of Figure 1;

40 Figure 6 is a section on the line 6—6 of Figure 5; and

Figure 7 is an enlarged fragmentary longitudinal section taken on the line 7—7 of Figure 1.

45 A slide constructed according to the present invention has many features in common with the slide disclosed in my prior application referred to above, these features being more particularly described in said prior application. Thus according to both the present and the prior inventions, the slide is of such weight that it can be easily handled and transported by a child, and is of such length that it can be readily passed thru an 50 ordinary doorway or stored in a closet of

usual size. The slide is so constructed that it will bear normally at both its ends on surfaces at various elevations, and may be supported at its upper end on various articles such as a tread of a stairway, a table-top, a bed, or the like, without fear of slipping, no special supporting means being required. The slide is convexly curved at its upper end to afford a seat for the child when mounting the slide and starting to coast, and also to afford a clearance space between the slide and the front edge of the flat surface on which its upper end is supported. The slide is concavely curved at its lower end so that it may rest on a flat surface such as a floor and discharge the 60 child substantially tangentially thereto without any drop. At its upper and lower ends the slide is provided with transverse bearing members which project laterally from the sides of the slide, thus adding to the stability of the slide, keeping it out of contact with base-boards, etc., and rendering it impossible for the child to pinch its fingers between the slide and the base-board.

65 The slide of the present invention differs from that disclosed in my said prior application in that it is provided with a relatively rigid delivery platform hinged thereto at its lower end. This platform is preferably long enough so that the child will come to a stop while still on the platform, thereby preventing injury to the child from contact with rough surfaces and lessening wear and tear on its clothes. The pivotal connection between the slide and the platform is such that the platform may be folded into the bed or channel of the slide in such position as to lie flat 70 against the flat portion of the slide. This construction enables the slides to be stacked one on top of the other in stores or warehouses, and facilitates packing, shipping and storing 75 of the slide. Moreover, instead of rounding the under surfaces of the transverse end bearing members, they are provided with rubber buttons preferably hemispherical in shape, 80 which construction serves the same purpose of giving normal, non-slipping support at much less expense. A further improvement is that one end of the slide is provided with small wheels, which enable it to be trundled from 85 place to place by a small child. The construction of the slide is also simplified in many respects, one particularly important change being that the convexly curved seat portion is 90 formed of sheet metal. This obviates the ne- 95 100 105 110

cessity of steaming and bending the hard maple slats forming the slideway, thus materially reducing the cost of manufacture of the slide.

Referring more particularly to the drawings, in which like reference characters denote like parts throughout the several views thereof, my improved slide comprises a pair of side flanges or beams 10, upper and lower transverse end bearing members 11, cross members 12, slats 13 forming the slideway or channel of the slide, and a seat portion 14.

The end bearing members 11 and the cross members 12 may be secured to the under sides of the side flanges 10 in any suitable manner. These parts are preferably made of wood, in which case ordinary wood screws or nails may be employed as the fastening means. The shape and positioning of these members are clearly shown in Figures 1 and 2.

The longitudinal slats 13, preferably of hard straight grained maple, extend from the top cross member 12, to the lower bearing member 11, and form the slideway of the slide. The lower ends of the slats 13 are slightly curved as shown in Figure 7 in order to deliver the child substantially tangentially as above explained, but this slight curve may be made without expensive steaming and bending operations. The slats may be secured to the upper cross member 12 by wood screws or clinch nails 15, as these are subsequently covered by the seat portion 14, and the slats adjacent the beams 10 may be secured to the lower cross members by suitable round-head counter-sunk screws or round-head clinch nails 16 as these are in such position that the child's clothes will not catch thereon. If screws or nails were used to fasten down the intermediate slats 13, however, they would be apt to catch the child's clothing and rip the same, as even though they were originally carefully counter-sunk they might loosen in time. To secure these intermediate slats to the cross members, therefore, I employ a fastener 17 which is more particularly shown in Figures 5 and 6. This fastener 17 comprises a strip of thin sheet metal the sides of which adjacent its ends are provided with sharp teeth or serrations 18. This strip is bent to the shape shown in Figure 6, and one of these fasteners is placed around each of the lower cross members 12 between each pair of slats 13. As shown in Figure 6, these fasteners are of such size as to come below the top surface of the adjacent slats 13, so that there will be no danger of the child's clothing catching thereon.

In assembling the slide, the cross members 12 and the lower bearing member 11 are first properly spaced, and one of the outer slats 13 fastened in place by screws or nails 15 and 16. One of the fasteners 17 is then slipped over each of the lower cross members 12 adjacent thereto. The next slat 13 is then placed on top of the cross members 12 and forced

sidewise by means of a suitable clamp until the teeth 18 bite into the wood of the two slats as shown in Figure 5. The slat thus placed may then be secured to the top cross member 12 by screws 15. This process is continued until the last slat 13 has been thus placed, when it may be secured to the lower cross members by screws 16. It will thus be seen that the fasteners 17 serve the triple purpose of fastening the slats 13 to the cross members 12 and to each other and spacing them the proper distance apart. The assembled unit thus formed is then nailed or screwed to the side flanges 10 and the upper bearing member 11 with the seat portion 14 in place.

It will be noted that the middle slats 13 are not secured to the lower end bearing member 11. For the reasons above stated, it would be inadvisable to use screws at this point, and if fasteners 17 were employed, it would be necessary to cut grooves in the member 11 to receive the same, as otherwise they would project slightly at the end of the slide. Since the slats 13 are curved at this end, their natural resiliency will hold them tightly against the member 11, and fastening means may therefore be safely dispensed with as a matter of economy and ease of manufacture. It is to be understood, however, that fasteners 17 could be used here if desired, and also that these fasteners might be employed on the top cross member 12 and between the outer slats 13 and the side beams 10.

The transverse bearing members 11 extend beyond the side flanges 10 at each end of the slide, and are provided with a plurality of hemispherical rubber buttons 19 on the bottoms thereof, which serve as convex bearing surfaces as described in my prior application referred to above. The end bearing member 11 at the lower end of the slide may if desired be provided with small rubber-tired wheels 20 which may be rotatably mounted thereon in any suitable manner. These wheels permit the child to trundle the slide from point to point by grasping the extended portions of the upper end bearing member 11.

In order to cheapen the construction of the slide as above explained, the seat portion 14 at the upper end of the slide is preferably formed of a rectangular piece of sheet metal bent to the form shown in Figure 4, and extends from the upper end bearing member 11 to the upper cross member 12. As best shown in Figure 3, this piece of sheet metal is fastened at either side under the side flanges 10, and between the same and the top cross member 12. It is designed to cover the upper ends of the slats 13 so that the child is delivered smoothly from the seat portion to the slideway of the slide. The seat 14 is provided with a central longitudinal groove 21 as shown in Figures 1 and 3, and may be secured to the top cross member 12 by means of a nail or similar fastening device 22 situated

in said groove. By this construction the head of the nail 22 is sufficiently below the top surface of the slide to prevent the child's clothing from catching thereon. The top edge of the seat is bent as shown in Figure 4 and is inserted into a groove in the upper transverse end bearing member 11 as illustrated in Figure 4. This construction very much lessens the cost of manufacture of the slide, as it obviates the necessity of steaming the slats 13 to the shape of the curved seat portion, and also shortens the same for a given length of the slide.

A straight delivery platform 25 is hinged to the lower end of the slide, and is adapted to lie flat upon the ground or floor on which the child is delivered by the slide.

The child will have stopped before it reaches the end of the platform 25, and this will eliminate the excessive wear on its clothing and the possibility of injury which are present when the child is delivered on a rough surface, as for example, a concrete sidewalk or a shivery wooden floor.

The construction of the platform 25 may be substantially similar to that of the slideway. That is, it is constructed of longitudinal slats 26 held together by cross members 27, and the securing means may be similar to those above described.

In order that the slide may be readily packed for shipment or storage and also may be stacked one on top of each other in stores and warehouses, it is desirable that the flat platform 25 should lie against the flat portion of the slide when folded. In order to accomplish this purpose, it is necessary that a sliding hinge construction be provided which will enable the pivoted end of the platform 25 to be moved up adjacent the lower end of the straight portion of the slide. A structure suitable for this purpose is shown in Figures 1, 2 and 7, and comprises bent rods 30 inserted into holes in the upper cross member 27 of the platform, and having eyes 31 formed at their free ends, through which is passed a transverse rod 32. The ends of the rod 32 are doubled over as shown at 33 after it has been put in place in order to prevent it from

slipping out of the eyes 31. The transverse rod 32 is mounted to slide freely in the direction of the length of the slide on the under side thereof, between the lower cross member 12 and the lower end bearing member 11. When the rod 32 is in its lowest position and the platform 25 swung outwards, the platform 25 will form a continuation of the slide. When it is desired to fold up the slide, the platform 25 is swung up against the same, which is permitted by the eyes 31 rotating on the rod 32, and the rod 32 is then moved into its upper position shown in dotted lines in Figure 7, when the platform 25 will fit against the flat portion of the slide as there shown.

The rods 30 are mounted above the lower end

bearing member 11, and fit in the spaces between the side flanges 10 and the adjacent slats 13.

Many alterations or modifications might be made in the structure above described without departing from the spirit of my invention, and such changes as fall within the scope of the appended claims are within the intent of my invention.

Having thus described the invention, what is claimed as new and desired to be secured by Letters Patent is:

1. A child's exercising and amusement slide comprising in combination, a pair of side flanges, a plurality of cross members secured thereto, a plurality of longitudinal slats forming the slideway of the slide, and metallic members having serrated edges adapted to bite into the sides of said slats and maintain them in fixed relationship, said members being positioned below the top surface of said slats.

2. A child's exercising and amusement slide comprising in combination, a pair of side flanges, a plurality of cross members secured thereto, a plurality of longitudinal slats forming the slideway of the slide, and a plurality of substantially U-shaped metal strips with serrated end portions for securing said slats to the cross members and to each other.

3. A child's exercising and amusement slide having a convexly curved seat portion at its upper end and comprising in combination, a pair of side flanges, a plurality of cross members secured thereto, a plurality of longitudinal slats forming the slideway of the slide, and a curved sheet metal member forming said convexly curved seat portion and overlapping said slats.

4. A child's exercising and amusement slide having transverse end bearing members secured to the under side thereof at each end and projecting laterally therefrom, and a plurality of rounded rubber buttons secured to the bottom surface of each of said bearing members, whereby the slide may be supported normally on surfaces at various elevations.

5. A child's exercising and amusement slide having transverse end bearing members secured to the under side thereof at each end and projecting laterally therefrom, and a pair of wheels rotatably mounted on one of said end bearing members, whereby the slide can be trundled from place to place.

6. In combination with a child's exercising and amusement slide having a curved lower end and provided with a slot, a relatively rigid flat delivery platform, and means for pivoting said platform to the lower end of said slide, said means comprising a transverse rod adapted to move longitudinally of said slide on the under side thereof, and a connecting member pivotally secured to said

rod, extending through said slot and pivoted to said platform.

7. In combination with a child's exercising and amusement slide, a relatively rigid delivery platform, and means for pivoting said platform to the lower end of said slide, said means comprising a transverse member mounted for sliding movement longitudinally of the slide on the under side thereof, and a pair of connecting links each pivotally secured at one end to said transverse member, and at the other to said platform.

8. In combination with a child's exercising and amusement slide, having a straight portion and a curved lower end and provided with side flanges, a relatively rigid delivery platform, means slidably and pivotally connecting said platform to the lower end of said slide, whereby the platform may be folded so as to overlie the face of the slide, and extend back onto the straight portion between the side flanges.

9. The combination with a child's exercising and amusement slide having a straight portion and curved lower end portion, of a delivery platform forming a continuation of said lower end, and slidable link means securing said platform to the slide for retraction into the slide to a position adjacent said straight portion.

10. A child's exercising and amusement slide, comprising in combination, a pair of side flanges, a plurality of longitudinal slats forming the slideway of the slide, each of said side flanges being spaced from its adjacent slat leaving a slot therebetween, a delivery platform forming a continuation of the lower end of the slide and of less width than the slide, and means extending through said slots and securing said platform to the slide

for retraction into the slide to a position spaced from said end.

11. The combination with a child's exercising and amusement slide, of a delivery platform forming a continuation of the lower end of the slide and comprising a plurality of transversely spaced slats, and means securing said platform to the slide for folding back onto the surface of said slide, with the slide surface of the platform adjacent the slide surface of the slide.

12. The combination with a child's exercising and amusement slide, of a delivery platform forming a continuation of the lower end of the slide and comprising a plurality of longitudinal slats, a plurality of cross members to which said slats are secured, and metallic members having serrated edges adapted to bite into the sides of said slats and maintain them in fixed relationship, said members being positioned below the top surface of said slats.

13. The combination with a child's exercising and amusement slide, of a delivery platform forming a continuation of the lower end of the slide and comprising a plurality of longitudinal slats, a plurality of cross members to which said slats are secured, and metallic members having serrated edges adapted to bite into the sides of said slats and maintain them in fixed relationship, said members being positioned below the top surface of said slats, and a plurality of substantially U-shaped metal strips with serrated end portions for securing said slats to the cross members and to each other.

In testimony whereof I hereunto affix my signature.

MEIER G. HILPERT.
